UNITED STATES PATENT OFFICE.

CASPER M. B. BOOS AND JOSEPH B. BOOS, OF MUSCATINE, IOWA.

LOCKING DEVICE FOR SAFES.

SPECIFICATION forming part of Letters Patent No. 761,194, dated May 31, 1904.

Application filed February 24, 1903. Serial No. 144,780. (No model.)

To all whom it may concern:

Be it known that we, CASPER M. B. Boos and JOSEPH B. Boos, citizens of the United States, residing at Muscatine, in the county of Muscatine and State of Iowa, have invented certain new and useful Improvements in Locking Devices for Safes, of which the following is a specification.

Our invention relates to and consists in certain improvements in the art of locking devices for safe-doors; and our invention is especially adapted for use in connection with round safe-doors.

Our object is to provide means of simple, durable, and inexpensive construction, whereby locking-segments carried by the door are forced into grooves designed to receive them in the safe-body, to thereby provide a strong lock which cannot become so easily broken or cut through, as would be possible with the use of any number of locking-bolts.

Our object is further and more specifically to provide means for projecting and withdrawing these locking-segments and also to provide improved means for making the mechanism which controls the movement of the locking-segments either operative or inoperative, said means to be governed by time or combination lock.

Our invention consists in certain details in the construction, arrangement, and combination of the various parts of the device, whereby the objects contemplated are attained, as hereinafter more fully set forth, pointed out in our claims, and illustrated in the accompanying drawings, in which—

Figure 1 shows an inside elevation of a safe-door provided with our improved locking mechanism, showing by dotted lines the position that the slide-bolt would assume when in its locked position and also showing by dotted lines the outline of one of the locking-segments and its operating-arm. Fig. 2 shows a sectional view of same on the indicated line 2 2 of Fig. 1. Fig. 3 shows in perspective the locking mechanism detached from the door, and Fig. 4 shows in perspective a modified form of the locking-segments.

Referring to the accompanying drawings, we have used the reference-numeral 10 to indi-

cate the safe-door, which is preferably formed complete of one piece of metal and is provided with a number of beveled surfaces 11 on its periphery, with shoulders 12 between them.

The numeral 13 indicates a conical spindle 55 extended through the central portion of the door with its base flush with the outer surface of the door, and in its base is an angular recess to receive a crank 14, by which the spindle may be rotated. The inner portion of the spindle is screw-threaded at 15, and a round nut 16 is screwed to this screw-threaded portion and held in place by a pin 17. In this nut 16 is a recess 18, for purposes hereinafter made clear, and the inner surface of the nut 16 is 65 flush with the inner face of the door. Surrounding the nut 16 is a circular rim 19, the inner surface of which is flush with the inner face of the door, and in this inner surface of the rim is a radial groove in which a bolt 20 70 is slidingly mounted, said bolt being capable of entering the recess 18 and also capable of entering a recess 21, formed in the inner face of the door.

The numeral 22 indicates a pin projecting 75 inwardly from bolt 20 and projected through a segmental slot 23, formed in a lever 24. This lever 24 is pivoted at 25 to the inner face of the door, and its other end is pivoted to an arm 26, which arm is moved by a lock 27. 80 The lock 27 is of ordinary construction and its parts are not illustrated. It is intended that either a time or combination lock may be used in this connection, its only object being to move the lever 24.

The locking-segments are indicated by the reference-numeral 28, and in the present instance we have shown three segments. These segments together form a complete circle and are set in a groove formed in the periphery 90 of the door near its inner face. To provide for projecting the edges of these rims beyond the periphery of the door, we have provided each segment with an integral arm 29, which arm is arranged tangentially relative to the rim 19 and is connected therewith by means of a pin 30 on the arm entering a groove 30^a in the rim 19. The arms move through openings provided in the door. Obviously when said rim is rotated in one direction all of the 100

segments 28 will be forced outwardly, and when the rim is rotated in an opposite direction they will be withdrawn into the body of the door. The grooves 30^a provide for a slight 5 movement of the arms 29 relative to the rim 19, so that the arms may move in straight lines.

In the modification illustrated in Fig. 4 we have shown a locking-segment which differs 10 from the preferred form in that the segment is provided with a number of integral projections 32, which projections are designed to enter a groove formed in the safe-body, and by this means a large number of locking 15 projections may be employed with comparatively little operating machinery.

In practical use and assuming the door to be in its locked position, with the locking-segments projected beyond the periphery of 20 the door, the bolt 20 is projected into the notch or recess 21, and the rim 19 is thereby positively held against rotation, so that the locking-segments cannot be withdrawn until this bolt in the rim 19 is withdrawn from the 25 recess 21. If when the parts are in this position the conical spindle should be rotated by means of the crank 14, it will be seen that this would have no effect upon the rim 19, as the said conical spindle and its nut 16 may freely 30 rotate, and the only way that the segments can be withdrawn is by first moving the lever 24 toward the lock 27 in such manner that the bolt 20 is projected into the recess 18 of the nut 16. When this is done, the rim 19 is 35 then connected with the nut 16 by means of the bolt 20, so that they will rotate in unison, and then as the operator turns the crank 14 in the proper direction the rim 19 may be rotated freely except as limited by the pin 22 in 40 the slot 23. This movement will have the effect of drawing each of the locking-segments to position with its periphery flush with the periphery of the door, and then the door may be freely opened. In locking the door the 45 crank 14 is turned and the locking-segments are projected, after which the time or combi-

nation lock 27 is operated in such manner as to force the bolt 20 into the recess 21.

Having thus described our invention, what we claim, and desire to secure by Letters Patent of the United States therefor, is—

1. The combination with a safe-door, having a notch on its inner surface, an arbor passed through the door, a nut fixed to the arbor and having a notch therein, a rim surrounding the 55 nut and rotatable thereon, a bolt slidably mounted in the rim and susceptible of being projected into either one or the other of said notches, a lock controlling the movements of said bolt, and a number of locking devices projected and withdrawn by the movements of said rim.

2. The combination with a round safe-door, having an annular groove in its periphery and a notch on its inner face, a conical arbor passed 65 through the door with its base outwardly, means for rotating the arbor from the outer surface of the door, a round nut fixed to the inner end of the arbor and having a notch therein, an annular rim in the inner face of 70 the door surrounding said nut and having a groove therein, a bolt slidably mounted in said groove and susceptible of being projected into either one of said notches, a lever fulcrumed to the inner surface of the door and 75 having a segmental slot therein, a pin passed through the slot and fixed to the bolt, a lock connected with the other end of the lever and moving it as required to project the bolt into either of said notches, a number of segmental 80 locking devices slidably mounted in the annular groove in the door, and an arm fixed to each segmental locking device and pivotally connected to the said rim, arranged and combined substantially in the manner set forth 85 and for the purposes stated.

CASPER M. B. BOOS.
JOSEPH B. BOOS.
